WOOD HEEL

Samuel G. Rosenberg, Roxbury, Mass.

Application February 1, 1943, Serial No. 474,241

4 Claims. (Cl. 36—34)

This invention relates to wood heels commonly used in the manufacture of women's shoes and attached by headed nails driven from inside the shoe.

The objects of my invention are to provide a wood heel which may be attached to a shoe more securely and reliably than heretofore and which is of such construction that relatively soft wood may be employed in its body. It has been the practice heretofore to use the hard woods, such as maple, for the bodies of wood heels. Hard woods have the advantage of supplying a firm holding for the attaching nails but it is difficult to drive the nails properly into them except under heavy pressure and there is always danger of splitting. Moreover, in war time conditions hard wood is not freely available as material for wood heels. Soft wood in heels has not heretofore been satisfactory because the attaching nails pull out too easily when subjected to very severe strains incident to wear. With these conditions in view, my invention consists in a novel wood heel having its heel seat formed of a thin resilient sheet which is secured to the finished heel as a part thereof, and is adapted to be punctured by and interlocked with corrugated or barbed heel attaching nails. The heel of my invention has two essential characteristics, first, that the resilient sheet be permanently secured in place as a part of the finished heel, and second, that the material of the sheet be puncturable by the attaching nails in such a manner as to interlock with them and oppose or substantially prevent withdrawal.

Various means for securing the resilient sheet in place in the heel may be adopted within the scope of my invention. As herein shown tacks or nails may be driven through the sheet into the body of the heel and in locations different from those of the heel attaching nails.

Preferably, and as a desirable feature of my invention the usual Celluloid heel cover may be flanged over the margin of the heel seat so as to engage and hold positively the edge of the sheet. If desired the folded margin of the Celluloid cover may be extended inwardly so as to be caught by the attaching nails, thus doubly securing the resilient sheet in its position.

The heel attaching nails to be employed in attaching the wood heel of my invention may be corrugated or barbed, with the result that in puncturing the resilient sheet they instantaneously displace its material in passing through the sheet and permit it then to contract resiliently upon the constrictions in the nail. The nails are thus interlocked with the resilient sheet by a

barbed ratchet-like or "monkey bite" engagement and are thus positively held in place against being withdrawn from the wood body of the heel. The result is a particularly secure, firm and reliable heel structure. When soft wood is employed in the heel it is firm enough to prevent lateral displacement of the attaching nails, while loosening or withdrawing of the nails is positively prevented by the resilient sheet which is secured to the heel by means other than the heel attaching nails.

It will be understood that the wood heel of my invention is completely finished by the wood heel manufacturer and distributed to the shoe maker ready for attaching in all respects. It may be handled by the shoe manufacturer exactly as all wood heels previously used by him and attached by the same machinery but supplied with heel attaching nails having corrugations which form alternate constrictions and enlargements in the body of the nail.

These and other features of the invention will be best understood and appreciated from the following description of a preferred embodiment thereof selected for purposes of illustration and shown in the accompanying drawing in which—

Fig. 1 is a view in perspective of the heel, a portion of the cover being shown as broken away,

Fig. 2 is a fragmentary cross sectional view on an enlarged scale,

Fig. 3 is a view in longitudinal section showing the heel attached to a portion of a woman's shoe, and

Fig. 4 is a view in perspective showing a resilient sheet or blank by itself.

The wood body 10 of the heel is formed by turning from a block in the manner well known in the industry, the only difference in the present case being that a slight allowance in height should be made for the thin sheet or blank which is to be added to its heel seat. The wood body of the heel herein shown is covered with sheet Celluloid 12, although leather or textile material may be employed. The bottom of the heel is covered by the usual top lift 11. To the concave heel-seat face of the heel is applied a thin resilient blank 14 which coincides in outline substantially with the heel-seat or may be slightly smaller if desired. The blank 14 may be of steel, brass or tin plate of slight spring temper or it may be hard, resilient fibre or sheet Celluloid. The essential characteristics are merely that it should be tough and not brittle and that it should be puncturable by the heel attaching nails which in the process deflect the material so as to form a crater closely fitting the body of the nail.

The blank 14 may be secured to the concave heel seat in any desired manner that will not interfere with the location of the heel attaching nails. As shown in Figs. 1 and 3 the tacks or short nails 15 are driven through the blank 14 at points along its central axis into the wood body of the heel. In this preliminary operation the blank 14 is concaved so that it makes face to face contact with the concavity of the heel seat and so fits it perfectly with its marginal edge held resiliently in intimate contact with the wood body of the heel.

Having partially secured the blank 14 in this manner the heel may be covered as usual and the covering material folded in over the margin of the heel seat, over the edge of the blank or sheet 14 and into binding engagement therewith. Where sheet Celluloid is used for the material of the cover, it is molded while softened by heat or solvent into exact conformity to the wood body of the heel. It is usually overlapped in the heel breast and its upper margin is inturned over the edge of the heel seat to form a peripheral flange 13 which overlies the entire edge of the blank 14, thus firmly and permanently securing it in position upon the heel seat. The inturned flange 13 may be actually cemented to the surface of the blank 14 and by reason of its relatively large area of contact supplies effective means for permanently uniting the thin resilient blank 14 to the wood body of the heel. If desired the flange 13 may be sufficiently wide to be caught by the heel attaching nails and the strength of the attachment thus even more increased. It will be understood that leather or textile material may be used in similar manner for heel covering material in place of Celluloid and that the blank 14 will be bonded or secured in place by cementing the cover material both to the wood body of the heel and to the blank.

Instead of preliminarily attaching the blank 14 by the tacks 15 it is contemplated in some cases that an attaching spur may be struck out from the body of the blank 14 as suggested in Fig. 4. As shown in this figure a pointed spur 18 is provided by driving a triangular punch through the material of the blank.

When the shoe manufacturer is ready to attach a heel constructed in accordance with my invention he has merely to present it to the wood heel attaching machine which has been supplied with headed attaching nails 17 of the character shown in Figs. 2 and 3. These attaching nails are corrugated or barbed so that the alternate enlargements and constrictions are formed in the body of the nail up to a point adjacent the head. A gang of these nails 17 may be driven at a single operation from inside the shoe, through the outsole 16 and into the wood body of the heel as shown in Fig. 3. In this operation the blank 13

is readily punctured by the nails, and in the material of the blank is formed an outwardly directed crater with sharp rough edges which bite against the material of the nails and find a constriction therein on account of the slightly resilient character of the material. The nails are thus positively interlocked with the blank 14 and since the blank itself is securely attached to the wood body of the heel any prying tension upon the heel tending to withdraw it from the heel attaching nails is positively resisted and a secure and reliable attachment thus achieved.

Having thus described my invention, what I claim as new and desire to secure by Letters Patent is:

1. A finished heel for women's shoes, comprising a body of relatively soft wood having a concave heel-seat, a thin resilient metal sheet concaved to fit said heel-seat surface and puncturable by heel attaching nails driven through it into the wood body of the heel, nails securing said sheet upon the heel, and a cover of stiff sheet Celluloid upon the exposed walls of the body of the heel molded over in a marginal flange permanently holding the entire edge of said metal sheet in position upon the heel-seat face of the heel.

2. In a woman's shoe having an outsole, a wood heel having a concave heel-seat, a thin resilient metal sheet conformed to said heel-seat, a Celluloid heel cover flanged over the margin of the heel-seat upon the edge of said sheet and holding the sheet permanently upon the heel, and barbed attaching nails driven through the outsole and said metal sheet into the heel and interlocked with the metal of said plate.

3. In a woman's shoe having an outsole, a heel comprising a body of relatively soft wood with a concave heel-seat, a thin resilient blank of sheet metal conformed to the heel seat and held with its marginal edge resiliently pressed against the heel seat surface, a heel cover overlapping said blank, and corrugated heel-attaching nails driven through the outsole into the body of the heel and interlocked with punctured edges of the said resilient blank.

4. A finished wood heel ready for attachment to a shoe and comprising a body of relatively soft wood having a concave heel-seat surface, a thin resilient sheet concaved to fit within the periphery of the heel-seat and adapted to be punctured by heel attaching nails driven through it into the body of the heel, means for securing said resilient sheet in position upon the heel, and a heel cover of sheet material upon the exposed curved surface of the heel, said cover being extended over the marginal edge of the heel-seat and flanged inwardly over the margin of said resilient sheet.

SAMUEL G. ROSENBERG.
